UNITED STATES PATENT OFFICE.

EUGENE H. CROWN, OF SACRAMENTO, CALIFORNIA, AND CHARLES T. WESTLAKE AND CHARLES S. SHALLENBERGER, OF ST. LOUIS, MISSOURI, ASSIGNEES TO FLORY CARRY IRON COMPANY, OF ST. LOUIS, MISSOURI, A CORPORATION OF DELAWARE.

DRAW-BAR CARRY-IRON.

1,148,150.

Specification of Letters Patent. Patented July 27, 1915.

Application filed March 6, 1914. Serial No. 822,891.

To all whom it may concern:

Be it known that we, EUGENE H. CROWN, a citizen of the United States, residing at Sacramento, California, and CHARLES T. 5 WESTLAKE and CHARLES S. SHALLENBERGER, citizens of the United States, residing at St. Louis, Missouri, have invented a certain new and useful Improvement in Draw-Bar Carry-Irons, of which the following is a 10 full, clear, and exact description, such as will enable others skilled in the art to which it appertains to make and use the same, reference being had to the accompanying drawings, forming part of this specification, in 15 which—

Figure 1 is a top plan view of a striking plate with which a carry iron of our improved construction is combined. Fig. 2 is a front elevational view of the carry iron in 20 position on a striking plate. Fig. 3 is a vertical sectional view taken approximately on the line 3—3 of Fig. 2. Fig. 4 is a vertical section taken approximately on the line 4—4 of Fig. 2. Figs. 5 and 6 are perspective 25 views of bearings which are located in the striking plate and which support the hangers forming a part of our improved carry iron. Fig. 7 is a perspective view of one of the hangers. Fig. 8 is a top plan view of 30 one end of the carry iron.

Our invention relates to new and useful improvements in supports or hangers for the drawbars of railway cars, the principal 35 object of the invention being to provide a comparatively simple hanger which, under all conditions will readily accommodate itself to the backward and forward movement of the drawbar resulting from draft and buffing strains, and the lateral swing or 40 movement of the drawbar resulting from the passage of cars around curves in the track.

In view of the fact that the length of movement of a supported drawbar is practically equal in both directions, that is, longitudinally and transversely, the carry iron which supports said bar should be permitted to move freely in both directions and in order to prevent the drawbar from sliding 45 upon the surface of the carry iron, the latter should be supported in such a manner as to permit the drawbar to move longitudinally and transversely at the same time. To 50 accomplish this result, we propose to mount

the carry iron upon hangers which are supported from a fixed part of the car body, preferably the striking plate, by universal joints, which arrangement permits said carry iron to move freely in all directions under the influence of the supported drawbar. 55

As the movement of the drawbar in each direction is approximately three inches from its normal central position, the rise of said drawbar when swinging would be considerable if the hangers were short, but in our improved construction, hangers are provided which are of such length that the drawbar will be free to move the necessary distance 60 in any direction without contacting with the under surface of the striking plate. 65

A further object of our invention is to provide a drawbar hanger or support which can be readily assembled or taken apart, and which when in position for use, cannot become accidentally displaced by reason of undue vibration or jolting of the car or drawbar. 70

With the above and other objects in view, our invention consists in certain novel features of construction and arrangement of parts, hereinafter more fully described and claimed. 80

Referring by numerals to the accompanying drawings, 10 designates the base of a 85 striking plate which is applied to a car end sill or buffer beam in any suitable manner and formed integral with said base and projecting forwardly therefrom is a horizontally disposed plate 11 provided on its front 90 and ends with a vertically disposed wall or flange 12. The central portion of this striking plate is reinforced by integral webs or walls 13, which are arranged between the front wall 12 and the plate 10, and formed 95 in the plate 11 between these walls and the walls 12 on the ends of said plate are openings 14 for the accommodation of the upper ends of the carry iron hangers. Formed in one of the walls 13 is an aperture 15 and 100 formed on the plate 11 on the opposite side of the adjacent opening 14 is a bearing seat 16. This seat and the aperture 15 serve as bearings for the trunnions 22 of a pivot block 23, which latter is provided in its upper side with a seat 24 for one of the carry iron hangers. Formed in the other of the walls 13 is an inclined notch 20 and formed 105

on the plate 11 on the opposite side of the corresponding opening 14 is a bearing seat 21. This notch and seat serve as bearings for the trunnions 17 of a pivot block 18, 5 which latter is provided in its upper side with a bearing 19 for the upper end of one of the carry iron hangers.

One of the hangers forming a part of our invention is shown in Fig. 7, the same comprising a shank 25, with the upper end of which is formed integral, a loop 26, the upper end thereof being formed into a transverse journal 27. The lower end of the shank 25 is provided with a pair of oppositely arranged and horizontally disposed journals 28.

The carry iron as contemplated by our invention is formed in a single piece, preferably by casting, and comprises a pair of 20 heads 29 and an intermediate body portion 30, the same being provided with a pair of oppositely disposed bearing faces 31 which are preferably convex in cross section. One of these convex bearing faces is located 25 nearer to the longitudinal axis of the carry iron than the other, and thus, by reversing the position of said carry iron or turning it upside down, the height at which the supported drawbar is carried can be varied.

30 Formed through the heads 29 are vertically disposed inwardly extending slots 32 and formed in the upper and lower surfaces of said heads to the sides of these slots are seats or bearings 33 which are adapted to receive the journals 28. A bolt or like fastening device 34 is seated in the wall 13 immediately to the rear of the inclined notch 20 and in the adjacent end wall 12 and immediately over the upper end of the corresponding hanger, thereby providing means 40 for preventing the accidental displacement of the device while the same is in use.

In assembling our improved drawbar support the bearing blocks 18 and 23 are inserted through the loops at the upper ends 45 of the hangers with the journals 27 on said hangers occupying the bearings 19 and 24, after which said bearing blocks are positioned immediately over the openings 14 50 with the trunnions on the ends of said blocks occupying the bearings 14 and 16 and 20 and 21. The carry iron comprising the heads 29 and body 30 is now positioned between the hangers with the journals 28 positioned in the lower pairs of bearings 33.

As the supported drawbar shown by dotted lines in Figs. 2 and 3 moves longitudinally of the car under buffing or pulling strains, the carry iron will swing backward 60 and forward with said drawbar during which movement the trunnions on the ends of the bearing blocks 18 and 23 rock in their respective seats.

During the transverse swinging movement of the supported drawbar which takes

place during the passage of the car around a curve in the track, the carry iron on the lower ends of the hangers 25 swings transversely of the car during which movement the journals 27 and 28 rock in their respective bearings. 70

By our improved arrangement of mounting the carrier on the striking plate, the hangers for the carry iron are provided at their upper ends with substantially universal joints, and for this reason the supported drawbar can move longitudinally and transversely at the same time without appreciable wear or strain upon any of the parts of the support. 75

The entire carrier is comparatively simple, can be easily and cheaply manufactured, and is capable of being readily assembled or taken apart. 80

We do not desire to be limited to the exact 85 arrangement and details of construction herein shown and described, as it will be readily understood that the principle and characteristic features of the invention may be embodied in other devices differing specifically in detail more or less from those 90 herein shown and described.

We claim:

1. In a draw bar carrier the combination 95 with a support provided with openings and having pairs of bearings formed at the sides of said openings, which bearings are transversely disposed with respect to the supported draw bar, of a pair of pivot blocks provided with trunnions which occupy said 100 bearings, hangers supported from said pivot blocks, and a carry iron supported by said hangers.

2. In a drawbar carrier, the combination 105 with a support, of a pair of hangers, pivot blocks forming a connection between said hangers and the support, which pivot blocks are provided with trunnions which are seated in bearings in the support and with bearings which receive the upper ends of the 110 hangers, whereby said hangers are permitted to swing longitudinally and transversely with respect to the car to which the hanger is applied, and a drawbar carry iron supported by said hangers. 115

3. In a drawbar carrier, the combination 120 with a support, of a pair of pivot blocks mounted for rocking movement thereon, which blocks are transversely disposed with respect to the supported draw bar, hangers, the upper ends of which are provided with loops which engage in transversely disposed bearings formed in the pivot blocks, and a drawbar carry iron supported by said hangers. 125

4. In a drawbar carrier, the combination 130 with a pair of hangers provided with trunnions on their lower ends, of a carry iron, the ends of which are slotted to accommodate the hangers, and there being bearings

formed in the upper and lower faces of said carry iron adjacent to the slots therein to receive the trunnions on said hangers.

5. The combination with a support provided with openings and bearings formed to the sides of said openings, of pivot blocks positioned in said openings and mounted for rocking movement in said bearings, hangers suspended from said pivot blocks, and a

10 carry iron pivotally supported by said hangers.

6. The combination with a support provided with openings and bearings formed to the sides of said openings, of pivot blocks positioned in said openings and mounted for rocking movement in said bearings, hangers suspended from said pivot blocks, a carry iron pivotally supported by said hangers, and means seated in the support above one of

the pivot blocks for preventing the withdrawal of the adjacent pivot blocks from its bearings.

In testimony whereof I hereunto affix my signature in the presence of two witnesses, this 21st day of February, 1914.
